CLAIM

The ornamental design for a jewellery box, as shown and described.

DESCRIPTION

FIG. 1 is a first perspective view of a jewellery box showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an exploded view of the jewellery box thereof; and,

FIG. 10 is a perspective view of another state of the jewellery box thereof.

The broken lines shown in the drawings depict portions of the jewellery box in which the design is embodied that form no part of the claimed design.
